AUTOMATIC LETTER OPENER

William Macowski, Caldwell, N.J., assignor to Ketcham & McDougall, Inc., Roseland, N.J.

Filed May 19, 1972, Ser. No. 255,313

Term of patent 14 years

Int. Cl. D18—04

U.S. Cl. D8—61

FIG. 1

FIG. 2

FIG. 3

FIG. 4

FIG. 5

FIG. 1 is a perspective view of an automatic letter opener showing my new design;

FIG. 2 is a top plan view;

FIG. 3 is a front elevational view;

FIG. 4 is a rear elevational view; and

FIG. 5 is a right side elevational view, the side not shown being a mirror image thereof.

I claim:

The ornamental design for an automatic letter opener, as shown and described.
